UNITED STATES PATENT OFFICE.

THOMAS LANDON, OF KUNCKLE, PENNSYLVANIA.

WASHING-MACHINE.

SPECIFICATION forming part of Letters Patent No. 605,962, dated June 21, 1898.

Application filed January 28, 1897. Serial No. 621,071. (No model.)

To all whom it may concern:

Be it known that I, THOMAS LANDON, a citizen of the United States, residing at Kunckle, in the county of Luzerne and State of Pennsylvania, have invented a new and useful Washing-Machine, of which the following is a specification.

The invention relates to improvements in washing-machines.

10 The object of the present invention is to improve the construction of washing-machines and to provide a simple, inexpensive, and efficient one, capable of rapidly and thoroughly washing clothes without injuring the fabrics and at the expenditure of a minimum amount of labor.

15 The invention consists in the novel construction and arrangement of parts, herein-after fully described, illustrated in the accompanying drawings, and pointed out in the claim hereto appended.

20 In the drawings, Figure 1 is a perspective view of a washing-machine constructed in accordance with this invention. Fig. 2 is a 25 longitudinal sectional view, the cover being open and the upper rubber being swung backward to afford access to the interior of the washing-machine. Fig. 3 is a transverse sectional view. Fig. 4 is a detail perspective 30 view of the upper oscillating rubber. Fig. 5 is a detail perspective view of the metal frame of the upper rubber.

Like numerals of reference designate corresponding parts in the several figures of the drawings.

35 1 designates a washing-machine body supported by suitable legs 2, provided with a curved bottom and having open vertical bearing-slots 3 at its opposite sides. Within the 40 body 1 are arranged upper and lower reversely-oscillating rubbers 4 and 5, provided with journals 6 and 7, which are arranged in the bearing-slots 3 of the sides of the body.

The upper and lower oscillating rubbers 45 are substantially semicylindrical, the upper rubber being sufficiently smaller than the lower one to fit within the same, as shown. The lower rubber 5 is provided with an inner curved rubbing-surface 8, formed by corrugations of transverse strips 9, which connect the sides of the lower rubber.

The upper rubber 4 is composed of segmen-

tal side pieces and transverse bars 10, which have their lower or outer edges sigmoidally curved to provide a rubbing-surface, and the 55 projecting portions of the edges of the transverse bars 10 are alternately arranged in order to bring the projections of one bar opposite the depressions of the adjacent bars. The long curves of the bars 10 of the upper 60 rubber, combined with the reverse arrangement of the bars, so that the projections of one bar occur opposite the depressions of the other, produce pronounced pockets and provide a more effective rubbing-surface than 65 that of the lower rubber, whereby the upper rubber is adapted to carry the clothes with it over the surface of the lower rubber.

The reversely-oscillating rubbers are operated by a crank-shaft 11, journaled in posts 70 or supports 12 at the rear or hinged end of a cover 13, and the said shaft 11 is provided with a central crank-bend 14 and a crank-arm 15, which is located at one end of it. The central crank-bend is connected by a pitman 75 16 with an arm 17, which is rigid with the rubber 4 and which extends through a longitudinal slot 18 of the cover, and the crank-arm 15 is connected by a pitman 19 with an arm 20 of the lower rubber 5. The arm 20 of 80 the lower rubber 5 is located at one side of the washing-machine body and is preferably formed integral with the adjacent journal 7.

The arm 17 is centrally connected with the upper rubber by means of a metal frame 21, 85 consisting of a transverse bar and arms arranged in pairs extending laterally from the end of the transverse bar and secured to the upper edges of the sides of the upper rubber, and the journals 6 are formed integral with 90 the metal frame 21.

The crank-shaft carries a balance-wheel 22, which is also provided with a crank-handle 23.

The arm 17 of the upper rubber is shorter than the arm 20 of the lower rubber, as clearly 95 illustrated in Fig. 3 of the accompanying drawings, and by this construction the upper rubber is caused to travel slightly faster and farther than the lower rubber. The greater movement of the upper rubber is sufficient to 100 produce a squeezing action on the clothes at the end of each oscillation, and the movement of the upper rubber, combined with the particular construction of its rubbing-face,

enables it during its oscillation to turn the clothes, carry them over the lower rubber to rub them, and squeeze them between it and the lower rubber at the end of each oscillation.

5 The journals are loosely arranged in the vertical bearing-slots of the sides of the washing-machine body, and the upper rubber is adapted to move vertically to adjust itself to the quantity of clothes interposed between it and the lower rubber to be washed. When the cover is swung backward, as illustrated in Fig. 2 of the accompanying drawings, it carries the upper rubber with it, so as to afford access to the washing-machine body.

10 15 The cover is supported, when swung backward, by a brace or prop 24, composed of two sections pivoted together at their inner ends and similarly attached at their outer terminals to the cover and to the washing-machine body.

20 25 It will be seen that the washing-machine is simple and effective, that the upper rubber, by being more pronounced than the lower one, is enabled to pick up the clothes, turn them over, and carry them with it over the surface of the lower rubber, and that at the end of each oscillation of the upper rubber the clothes are squeezed to expel the dirt and water from them and cause the former to be 30 carried off by the latter through the spaces between the bars 9 and 10 of the rubbers.

What I claim is—

In a washing-machine, the combination of

a washing-machine body provided at its sides with vertical slots, a lower rubber having an inner concave rubbing-surface and provided with journals arranged in said slots, an upper rubber mounted in the slots of the washing-machine body and provided with a convex rubbing-surface consisting of a series of transverse bars 10 provided at their lower edges with longitudinal curves substantially sigmoidal, the projections of one bar being disposed opposite the depressions of the adjacent bars to form enlarged pockets, the rubbing-surface of the upper rubber being more pronounced than that of the lower rubber and capable of obtaining a greater hold on the clothes to cause them to be carried by the upper rubber, the arms 17 and 20 connected with 45 and extending upward from the upper and lower rubbers, the arm 17 of the upper rubber being shorter than that of the lower rubber, whereby the said upper rubber is caused to travel faster and farther than the lower one, a double-crank shaft, and pitmen connecting the arms 17 and 20 with the crank-shaft, substantially as and for the purpose described.

In testimony that I claim the foregoing as my own I have hereto affixed my signature in the presence of two witnesses.

THOMAS LANDON.

Witnesses;

ALFRED J. BARBER,
W. G. ROCKAFELLOW.
